UNITED STATES PATENT OFFICE.

ROBERT LEE ETTENGER, OF WASHINGTON, DISTRICT OF COLUMBIA.

SAFETY-CAP FOR BOILER-PLUGS.

1,248,297.

Specification of Letters Patent. Patented Nov. 27, 1917.

Application filed April 19, 1917. Serial No. 163,150.

To all whom it may concern:

Be it known that I, ROBERT L. ETTENGER, a citizen of the United States, residing at Washington, in the District of Columbia, have invented certain new and useful Improvements in Safety-Caps for Boiler-Plugs; and I do hereby declare the following to be a full, clear, and exact description of the invention, such as will enable others skilled 10 in the art to which it appertains to make and use the same.

This invention relates to boiler construction, and more particularly to plug caps or plug retaining and safety appliances used 15 in connection with locomotive boilers of any type wherein a plug cap is necessarily used in order to prevent the plugs from blowing out when undue force is concentrated against them.

It has been the common method to tap the fire box sheets and use threaded screw plugs which engage the interiorly threaded holes in the sheets, but the action of the flue cleaner and ordinary corrosion of the metal 25 soon decays the threads as well as the great wear on the threads of both the plugs and boiler that necessarily follows from the frequency of removal for washing out, which must be done in order to keep the tubes free 30 from all deposits as explained above; so that failure to inspect or oversight in providing new plugs presents the danger of their blowing out and a consequential damage. It is the purpose of this invention 35 therefore to provide a means whereof a protecting cap may be applied to prevent such occurrences and to provide further a simple and inexpensive device of the character referred to which may be used in connection 40 with any boiler to insure the retention of a plug within its socket and which may be quickly and readily applied when needed.

The invention will first be hereinafter more particularly described, with reference 45 to the accompanying drawings, which are to be taken as a part of this specification, and then pointed out in the claims at the end of the description.

In the drawings, Figure 1 represents a 50 partial sectional view of the interior of a locomotive boiler showing the location of the water tubes and washout plugs in association therewith, and my improved plug retaining safety device applied thereto;

55 Fig. 2 is a partial transverse sectional view of my specific improvement as adapted to be

used with a plug having a projecting polygonal portion for applying an ordinary wrench;

Fig. 3 is a front elevation of the bracket 60 or plate member, in position;

Fig. 4 is a slight modification thereof;

Fig. 5 represents a slight modification of the bracket or plate member as adapted to be used in connection with plugs which have a 65 polygonal cavity instead of a nut-like portion;

Fig. 6 is a sectional view similar to Fig. 2 of said modification;

Fig. 7 is also a transverse sectional view 70 of another modification; and

Figs. 8 and 9 are further modifications of the bracket member.

In the drawings, in which the same reference letters are used to denote corresponding parts in different views, the letter A 75 may denote a locomotive boiler and a and a^1 the back head and flue sheet thereof, respectively. The water tubes suitably mounted within said flue sheet and back sheet may 80 be designated by a^2 . The washout plugs 1 are commonly threaded and screwed into suitably internally threaded passages or holes in the throat sheet and in the back head of the boiler and the said passages are 85 preferably in a direct line with the ends of the water tubes to facilitate the washout process.

The plug 1 having the usual boiler-plate engaging threads 2 is provided on its head 90 with a rounded shoulder 3 and a tool-engaging member or projection 4 for turning the same. Surrounding the projection 4 and adapted to fit over the same but preferably spaced therefrom to allow perfect adjustment as hereinafter described, is the plug retaining means, in certain of the figures shown as a plate or cap 5 provided with an aperture 6 preferably arranged centrally thereof and two lateral wings or arms 7. 100 The central aperture 6 is provided peripherally thereof on one or both sides of the plate 5 with rounded seat or ball joint 8 which is adapted to receive the similarly rounded shoulder 3 of the plug proper providing a 105 ball joint against which the plate or cap bears. Obviously, the same universal adjustment or ball and socket is afforded by having either the plug or plate rounded and the corresponding member plain or not 110 rounded. The lateral wings or arms 7 are provided with apertures 9 for engaging the

plate retaining means herein shown as two studs 10 passing therethrough and threaded into the boiler-plate on each side of the plug 1.

5 The plate or cap retaining devices may take any desired form, such as riveted studs provided with disengageable heads or in fact, any similar disengageable fastening means may be used.

10 In Fig. 4, the plate 5 is shown as having open sided apertures 11 for the reception of the bolts or similar members 10, so that the plate can be removed more speedily. Fig. 5 shows a similar arrangement of the plate 15 illustrating also the central aperture 12 as open sided.

Fig. 6 shows a modification of the projection 13 of the plug 1 and in this case said projection is made round and interiorly 20 formed to take the turning tool, as at 14.

Fig. 7 illustrates a further embodiment of the invention, wherein the plug 1 is provided with a recessed portion 15, of any desired shape, herein shown as square and 25 adapted to receive a correspondingly shaped stud 16 formed integral with the plate or cap. The plate is provided with the before described fastening means.

Figs. 8 and 9 show the variant shapes 17 30 and 18 respectively of which the plate member may be made and is also shown as provided with the apertures for the plug projection and fastening means.

It will of course be understood that various 35 other forms of my improvement may be

constructed without departing from the spirit and scope of my invention as set forth in the appended claims.

Having thus described my invention, what I claim as new and desire to secure by Letters Patent is:

1. In combination with a boiler-plate, a plug threaded therewith, and means detachably connected to said boiler-plate and adapted to prevent said plug from blowing out due to defective threaded connection; said plug being provided with a rounded shoulder adapted to bear against said first mentioned means.

2. In combination with a boiler-plate, a plug threaded therewith, and means detachably connected to said boiler-plate adapted to prevent said plug from blowing out due to imperfect threaded connection; said means including a universal bearing surface 55 between said plug and said means.

3. An article of manufacture comprising a washout plug including a portion provided with threads adapted to hold the plug in a correspondingly threaded opening of a boiler-plate, said plug being also provided with a rounded portion adapted to contact with an auxiliary plug retaining member.

In testimony whereof I affix my signature in the presence of two witnesses.

ROBERT LEE ETTENGER.
